UNITED STATES PATENT OFFICE

166,670

TANK TRUCK BODY

Clarence Hoppel, Blair, Nebr.

Application September 5, 1950, Serial No. 12,064

Term of patent 14 years

(Cl. D14—3)

To all whom it may concern:

Be it known that I, Clarence Hoppel, a citizen of the United States, residing at Blair, State of Nebraska, have invented a new, original, and ornamental Design for a Tank Truck Body, of which the following is a specification, reference being had to the accompanying drawing, forming a part hereof.

Figure 1 is a side elevation of the tank truck body embodying the features of the invention;

Figure 2 is a side elevation of the opposite side of the tank truck body, as shown in Figure 1;

Figure 3 is a top plan of the tank truck body; and

Figure 4 is a rear view of the truck body.

The dotted lines shown in the drawings are for illustrative purposes only.

I claim:

The ornamental design for a tank truck body, as shown and described.

CLARENCE HOPPEL.
